117,069

DESIGN FOR A COMBINED PERFUME CONTAINER AND BOX THEREFOR

Florence N. Lewis, New York, N. Y.

Application August 2, 1939, Serial No. 86,406

Term of patent 3½ years

To all whom it may concern:

Be it known that I, Florence N. Lewis, a citizen of the United States, residing at New York, in the county of New York and State of New York, have invented a new, original, and ornamental Design for a Combined Perfume Container and Box Therefor, of which the following is a specification, reference being had to the accompanying drawing, forming part thereof.

In the drawing

Fig. 1 is a perspective view of a combined perfume container and box therefor showing my new design, the box being shown in closed position.

Fig. 2 is a front perspective view of the article shown in Fig. 1 with the box in open position and the top removed.

I claim:

The ornamental design for a combined perfume container and box therefor, as shown and described.

FLORENCE N. LEWIS.
